UNITED STATES PATENT OFFICE.

JULIUS K. LUX, OF JERSEY CITY, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,092,779.

Specification of Letters Patent.

Patented Apr. 7, 1914.

Application filed July 15, 1910. Serial No. 572,073.

To all whom it may concern:

Be it known that I, JULIUS K. LUX, a citizen of the United States, residing in Jersey City, in the county of Hudson and State of New Jersey, have invented certain new and useful Improvements in Type-Writing Machines, of which the following is a specification.

This invention relates to mechanisms for turning the platen forwardly or backwardly for a part of a regular line-space to enable the types to print above or below the usual line of writing; and is in the nature of an improvement on United States Patent to Forkarth No. 918,308, dated April 13, 1909. In said Forkarth patent, the fractional line-spacing is effected by means of a dog which normally stands disengaged from the usual platen line-space wheel, but which may be moved by the operator in one direction into engagement with said wheel and in another direction to rotate the platen either forwardly or backwardly, as the case may be.

One of the objects of the present invention is to simplify the manipulation of the device, and to this end I provide a finger-lever which normally stands in a central position, but which may be swung therefrom either directly forward or directly back, as far as it will go, thereby positioning the platen in the manner required. This finger-lever has means for first setting and then operating the dog which directly engages and operates the line-space wheel.

The operation of the finger-lever from idle position, either forwardly or backwardly, first throws the dog or dog-lever into engagement with the platen ratchet, or line-space wheel; continued movement of the finger-lever in the same direction causes the dog to swing the ratchet and platen through part of a regular line space.

Another object of the invention is to enable the fractional line-space interval to be regulated.

Other features and advantages will hereinafter appear.

In the accompanying drawings, Figure 1 is a rear perspective of one form of the invention applied to an Underwood front-strike writing machine, showing the parts in normal positions. Fig. 2 is a side view thereof. Fig. 3 is a similar view, showing the positions of the parts when the mecha-

nism has been operated to throw the dog into the line-space ratchet. Fig. 4 shows the positions of the parts when the finger-lever has completed its throw in one direction. Fig. 5 shows the positions of the parts during the first portion of the return stroke of the finger-lever to normal or idle position. Fig. 6 is similar to Fig. 4, but showing the finger-lever at the opposite limit of its movement. Fig. 7 is a sectional plan. Fig. 8 is a detail perspective of the dog and its tooth. Fig. 9 is a detail perspective of the cover plate. Fig. 10 shows one of the adjustable stops. Fig. 11 is a side view of the mechanism in normal position. Fig. 12 is a similar view, full lines showing the positions of the finger-lever and dog-lever at one limit of their movement, dotted lines showing the opposite positions of the parts.

A platen 1 has an axle 2 journaled in the platen frame end 3 of an Underwood writing machine. Line-space mechanism, mounted on one of the platen frame ends, comprises a lever 4, operating a slide 5, carrying a pawl 6 to act upon a ratchet wheel 7 fast on the axle, to turn the platen through one or more regular line-spaces. This mechanism is normally protected by a cover plate 9, having a depending flange or apron 10. A spring-pressed detent 8 engages the line-space ratchet. The ratchet is also equipped with a fractional line-spacing mechanism comprising a finger-lever 11 pivoted at 12 to a mount 13 secured to the apron or flange 10 of the cover plate, to swing in opposite directions from its normal central position, to turn the platen forwardly or backwardly. Said finger-lever has a cam slot 14 having divergent cam faces 21, 22, terminating in shoulders 23, 26, the latter formed at angles to abutments 24, 27, forming the ends of the slot 14. These cam-faces, etc., are employed in operating the dog-lever, causing it to engage the line-space ratchet and turn the latter, as will presently be explained. Oppositely-facing returning abutments 25 and 28 project into the cam slot, intermediate its ends; said slot in effect forming two oppositely-turned elbow-slots joined together.

The finger-lever or handle acts upon a tooth 15, which projects through an opening 34 in the apron 10, into the cam slot 14, said tooth projecting from a dog 16. This

dog is in the form of a plate, lying against the face of the apron, and having a slot near one end by which it is loosely journaled upon the platen axle 2, to admit of 5 radial as well as vibratory or angular movements of the dog relatively to the platen axle. Said tooth 15 normally occupies the recess formed by the divergent cam faces 21, 22 of the cam slot 14, when the finger-lever 10 is in its normal central position, and is out of mesh with the line-space ratchet 7. Said tooth is yieldingly held in this position by a returning spring 18, bearing against the side of a headed stud 18^a, the head preventing 15 the disconnection of the spring. The pressure of the tooth 15 against the converging cam faces holds the finger lever in normal position.

The mount 13 has a guide wall 20 about 20 concentric with the line-space ratchet, and interrupted by a recess 19 projecting laterally therefrom to form a seat lying out of the path of the ratchet, for the tooth 15. The seat or recess 19 and the space between 25 the divergent cam faces 21, 22 of the cam slot 14 register when the lever is in its normal central position, to accommodate the tooth 15 which then lies clear of the ratchet 7. When the finger lever 11 is rocked in the 30 direction of the arrow (Fig. 2) to turn the platen rearwardly or counterclockwise, as viewed in Fig. 3, the cam face 22, which lies at an angle to the tooth 15, rides against the tooth to crowd the latter, together with 35 the dog 16, radially inwardly or toward the platen axis, against the tension of the spring 18, to mesh the tooth with the ratchet, and also to bring it into contact with the guide wall 20. The return of the tooth to 40 the recess 19 is now blocked by the interposition of the shoulder 23, which is caused by the lever to lie across the mouth of the recess (Fig. 3) when the tooth has been crowded out of said recess. At this time, 45 also, the finger piece 11 has brought the abutment 24 against the tooth 15, so that continued movement of the finger-lever in the direction of the arrow (Fig. 3) turns the tooth and ratchet to rotate the platen 50 through port of a regular line-space; the tooth 15 being held in mesh with the ratchet during such movement, by the guide wall 20. The dog 16 rocks about the axle 2, until arrested by contact with stop 29.

55 The platen may be held between two lines of writing, because of the frictional contact of the tooth 15 with fixed guide wall 20, to enable an operator to use both hands in writing. To return the platen to normal 60 position so as to print on the regular line of writing, the lever 11 is swung from the Fig. 4 to the Fig. 5 position, thereby moving the abutment 24 away from one side of the tooth 15 and bringing the returning abutment 65 25 against the opposite side of the

tooth to cause the latter, by pressing against tooth *b* of the ratchet, to return the latter and the platen to original position. When the lever 11 is moved from Fig. 2 to its Fig. 6 position, to turn the platen forwardly, the 70 cam face 21 crowds tooth 15 out of its seat 19 into mesh with the ratchet 7, the shoulder 26 blocking the return of the tooth, and the abutment 27 forcing the tooth against a tooth *b* of the ratchet, to turn the platen. 75 The latter is rotated until arrested by the contact of the arm 32^a of the dog with a stop 29^a. The tooth returns the platen to original position when acted upon by the lever-controlled returning abutment 28. 80 That portion of the tooth 15 which contacts with the guide or confining wall 20 is preferably given a flat face 15^a to prevent it from slipping into recess 19 on its return, before the ratchet 7 and platen have been 85 returned to their original positions. When the tooth is exactly opposite said seat 19, the spring 18 sets it thereinto, to disconnect it from the ratchet so as to afford no obstruction to the usual line-spacing operation; the swing of the lever to normal central position having brought the space between the divergent cam faces 21, 22, to 90 register with the seat 19 in time to accommodate the tooth. 95

The mount 13 is adjustably secured to the flange or apron 10 of the cover plate 9 by fastenings, as screws 31, 31^a, threaded in the mount and passing through slots 33, arranged about concentric with the line-space 100 ratchet wheel, said fastenings having washers 29, 29^a, which are clamped against the apron to hold the mount where adjusted in the slots. Such adjustment enables the device to be shifted to coöperate with different ratchet wheels, the opening 34 being of sufficient size to afford room for the tooth 15 to operate in any adjustment. Said washers 29, 29^a, also serve as stops to arrest the dog 16 and hence the 110 platen. The combined stops and washers preferably have rims 30, beneath which the dog lies when in contact with the stops, to prevent the dog from overthrow, if subjected to heavy pressure during a vigorous 115 operation of the lever 11. The washers are adjustable about the screws 31, 31^a, which pass eccentrically therethrough, to enable the throw of the platen to be varied, by varying the distance between the normal position of the dog and the washers. The dog may have laterally extending arms 32, 32^a, to engage the stops. 120

Variations may be resorted to within the scope of the invention, and portions of the 125 improvements may be used without others.

Having thus described my invention, I claim:

1. In a typewriting machine, the combination with a platen having a ratchet fixed 130

thereto, of a fractional line-space mechanism comprising a dog mounted for both radial and angular or vibratory movements relatively to the platen axle, and having a 5 tooth to engage the ratchet, and a lever to mesh the tooth with the ratchet and effective by pressure against the tooth to swing the latter to turn the platen through part of a regular line-space and to return it to 10 original position.

2. In a typewriting machine, the combination with a platen having a ratchet, of a shiftable tooth normally lying out of engagement with the ratchet, and a lever rocking 15 in opposite directions from a normal idle position to crowd the tooth into mesh with the ratchet to turn the latter and the platen forwardly or backwardly, said tooth being supported independently of the lever 20 and movable relatively thereto.

3. In a typewriting machine, the combination with a platen having a ratchet, of a shiftable tooth normally out of engagement with the ratchet, a guide wall having a guiding surface substantially concentric with the ratchet and interrupted intermediate its ends by a recess in which the tooth normally seats, a lever to rock in opposite directions from a 25 normal central position and having diverging cam faces, the space between which registers with the recess when the lever is in normal position, a shoulder to block the return of the tooth to its seat when dislodged therefrom by one or the other cam face, abutments controlled by the lever to return the 30 tooth to a point opposite its seat after it has been thrown in one direction or the other, by the lever to effect the partial rotation of the platen in one direction or the other, and 35 a spring to seat the tooth.

4. In a typewriting machine, the combination with a platen having a ratchet, of a dog movable radially and angularly relatively to the platen axle and having a tooth normally seated in a recess out of contact with the ratchet, a lever having divergent cam faces between which the tooth normally seats, to crowd the tooth out of its seat and into mesh with the ratchet, the lever rocking in 45 either direction from its normal central position, shoulders on opposite sides of the tooth to block its return to its seat, and abutments, one or the other of which is effective depending upon the direction of 50 stroke of the lever to press against the tooth and partially rotate the platen.

5. In a typewriting machine, the combination with a platen having a ratchet, of a dog radially and angularly movable relatively 55 to the platen axle and having a tooth normally seated in recess out of contact with the ratchet, a lever having divergent cam faces between which the tooth normally seats, to crowd the tooth out of its 60 seat and into mesh with the ratchet, the

lever rocking in either direction from its normal central position, and abutments, one or the other of which is effective depending upon the direction of stroke of the lever to press against the tooth and partially rotate 70 the platen.

6. In a typewriting machine, the combination with a platen having a ratchet, of a dog radially and angularly movable relatively to the platen axle and having a tooth normally seated in a recess out of contact with the ratchet, a lever having divergent cam faces between which the tooth normally seats, to crowd the tooth out of its seat and into mesh with the ratchet, the 75 lever rocking in either direction from its normal central position, abutments, one or the other of which is effective depending upon the direction of stroke of the lever to press against the tooth and partially rotate 80 the platen, and means controlled by the lever to return the tooth and platen to original position.

7. In a typewriting machine, the combination with a platen having a line-spacing mechanism including a ratchet, of a shiftable tooth normally out of contact with the ratchet, means controlled by a lever to mesh the tooth with the ratchet and turn the latter and the platen, a lug or abutment on the lever to engage the tooth and thereby return the ratchet and platen to original positions; and means limiting the stroke of said lever to less than a line-space movement of the platen.

8. In a typewriting machine, the combination with a platen having a ratchet, of a shiftable tooth normally seated in a recess communicating with a guide wall formed about concentric with the ratchet, a lever having an elbow slot one wall of which operates to cam the tooth into contact with the guide wall and into mesh with the ratchet, another wall of said elbow slot operating to force the tooth together with the ratchet and platen through a partial rotation, and a third wall of said elbow slot operating to return the tooth together with the platen and ratchet to original position.

9. In a typewriting machine, the combination with a platen having a ratchet, of a shiftable tooth normally seated in a recess communicating with a guide wall intermediate its ends, said guide wall formed substantially concentric with the ratchet, a lever having a double elbow slot to cam the tooth into contact with the guide wall and the ratchet to rotate the platen in either direction and to return the latter to original position, one wall of said elbow slot operating to cam the tooth into contact with the guide wall and into mesh with the ratchet, another wall of said elbow slot operating to force the tooth together with the ratchet and platen through a partial rotation, and a 115 120 125 130

third wall of said elbow slot operating to return the tooth together with the platen and ratchet to original position.

10. In a typewriting machine, the combination with a platen and a ratchet wheel, of an adjustably supported mount, having a guide wall lying concentric with the ratchet wheel with a laterally projecting seat or recess, a dog comprising a plate mounted on the platen axle to have both a radial and vibratory or swinging movement relatively to the platen axle, a tooth on the dog, a spring to hold the tooth normally in the seat or recess out of engagement with the ratchet wheel, a slotted lever pivoted on the mount, the tooth being accommodated in the slot in the lever, a cam face on the lever to force the tooth to co-act with the concentric portion of the guide wall and into engagement with the ratchet, a shoulder on the lever to block the return of the dog to the seat or recess, an abutment to swing said tooth and ratchet through part of a rotation, returning abutment on the lever to return the tooth to position to enter its seat and be disengaged from the ratchet, and a stop in the path of the dog to arrest the platen.

11. In a typewriting machine, the combination with a platen and a line-space wheel, of a platen frame in which the platen turns, a tooth to operate the platen, a lever to operate the tooth, and a mount having a guide wall with which the tooth co-acts, said mount supporting the lever, and being adjustably secured to the frame to adapt the mechanism to different line-space wheels.

12. In a typewriting machine, the combination with a platen and a line-space wheel, of a platen frame in which the platen turns, said frame having slots arranged concentric to the wheel, a mount, fastenings passing through the slots to secure the mount to the frame, a dog adapted for both vibratory angular and radial movements relative to the wheel, a tooth on the dog co-acting with a guide wall on the mount, a lever on the mount to operate the tooth and dog to turn the platen, and washers included in the fastenings and effective as stops to arrest the platen.

13. The combination with a platen and line-spacing mechanism including a line-space wheel and a detent, of a fractional spacing mechanism including a lever or handle movable forwardly and backwardly from a central normal position, a stop for arresting the lever, and a dog normally disengaged from said line space wheel, supported independently of the lever and movable by said lever during a single stroke of the latter in either forward or backward direction into engagement with said line-space wheel, and then in a direction to turn the latter.

14. The combination with a platen and a

line-spacing mechanism including a line-space wheel and a detent, of a fractional spacing mechanism including a lever or handle movable forwardly and backwardly from a central normal position, a stop for 70 arresting the lever, and a dog separate from the lever and normally disengaged from said line space wheel, and movable by said lever during a single stroke of the latter in either forward or backward direction, into engagement 75 with said line-space wheel, and then in a direction to turn the latter; said lever or handle mechanically held in said central normal position.

15. The combination with a platen, a line-space wheel and a detent, of a lever movable forwardly and backwardly from a central normal position, stops for arresting such movements of the lever, and a dog normally disengaged from said line space wheel, and movable by said lever during a single stroke of the latter in either forward or backward direction, first into engagement with said line-space wheel, and then in a direction to turn the latter.

16. In a typewriting machine, the combination with a platen having a ratchet, of a shiftable tooth normally lying out of engagement with the ratchet, and a lever having a cam surface to engage said tooth and crowd it into mesh with the ratchet, and an abutment to engage the tooth and turn the ratchet and platen.

17. In a typewriting machine, the combination with a platen having a ratchet, of a shiftable tooth normally lying out of engagement with the ratchet, a lever having a cam effective by its contact with the tooth to crowd the tooth into mesh with the ratchet and having an abutment to engage the tooth 100 and turn the ratchet and platen, and means to return the tooth to idle position.

18. In a typewriting machine, the combination with a platen frame and a platen having a ratchet, of a shiftable tooth normally disconnected from the ratchet, means forming a guiding surface for holding the tooth in engagement with the ratchet stationary with respect to the frame, a lever to press against the tooth when in mesh 110 with the ratchet to turn the platen, and a cam operated by the lever to crowd the tooth into mesh with the ratchet.

19. In a typewriting machine, the combination with a platen having a ratchet, of a guide wall having a guiding surface substantially concentric with said ratchet and having a recess, a shiftable tooth normally seated in said recess, and a lever effective to crowd the tooth out of the recess to mesh it with the ratchet, and thereafter to press the tooth along the said guiding surface to turn the ratchet and platen, said lever being provided with means to return the platen to original position.

20. In a typewriting machine, the combination with a platen having a ratchet, of a shiftable tooth normally seated in a recess out of contact with the ratchet, a lever, 5 means controlled by the lever to mesh the tooth with the ratchet and turn the latter and the platen, said lever having an abutment to engage the tooth to return the platen and ratchet to original position, and 10 a spring to seat the tooth out of engagement with the ratchet.

21. In a typewriting machine, the combination with a platen frame and a platen having a line-space wheel, said frame having slots concentric with said wheel, of a 15 mount having fastenings passing through the slots in the frame, said mount having a guide wall provided with a seat, a tooth accommodated in the seat and adapted to 20 traverse the wall, and a lever to operate the tooth, said lever being pivoted on the mount to be adjustable therewith relatively to the ratchet wheel.

22. The combination with a ratchet, of a 25 dog having a shiftable tooth normally disengaged from the ratchet and movable in one direction into engagement with the ratchet and in another direction to operate

the ratchet, means having cam surfaces to 30 guide the dog in said movements, and a lever movable in one direction to effect the two movements of the dog, said lever being provided with means to return the platen to original position.

23. In a typewriting machine, the combination with a platen and a ratchet, of a dog having a tooth normally out of engagement 35 with the ratchet, and a dog-actuating member having a cam surface and operable by a single movement to cam the dog into engagement with the ratchet and turn the platen, said member being provided with means to return the platen to original position.

24. In a typewriting machine, the combination with a platen and a ratchet, of a dog having a tooth normally out of engagement 40 with the ratchet, and a dog-actuating member having surfaces to respectively cam the tooth into engagement with the 45 ratchet and to move the dog and ratchet as a unit to turn the platen.
